[57] CLAIM

The ornamental design for a coping member for above-ground swimming pool, as shown and described.

DESCRIPTION

FIG. 1 is a front perspective view of a coping member for above ground swimming pool, showing my new design;

FIG. 2 is a top plan view of the coping member in accordance with my invention;

FIG. 3 is an end elevation thereof;

FIG. 4 is an end elevation thereof taken from the other end;

FIG. 5 is a front elevation thereof;

FIG. 6 is a rear elevation thereof; and,

FIG. 7 is a fragmentary enlarged perspective view of the coping.

The broken line showing of a swimming pool in FIG. 1 is for illustrative purposes only and forms no part of the claimed design.
